Attorney

UNITED STATES PATENT OFFICE.

ALBERT L. JONES, OF BROOKLYN, NEW YORK.

FABRIC FOR WINDOW-SHADES, &c.

SPECIFICATION forming part of Letters Patent No. 283,893, dated August 28, 1883.

Application filed May 14, 1883. (Model.)

To all whom it may concern:

Be it known that I, ALBERT L. JONES, of the city of Brooklyn, in the county of Kings and State of New York, have invented a certain 5 new and useful Improvement in Fabrics for Window-Shades, &c., of which the following is a specification.

The object of my invention is to produce a fabric, chiefly of paper or other suitable material, which can be used for window-shades, screens, wrappers, envelopes, bags, boxes, &c., which will possess durability, and may also be made very ornamental; and it consists in the production of an article of manufacture, being 10 a fabric composed of layers of paper or other suitable material having fibers of the same or of other material in the form of threads, cords, tape, ribbons, straw, or fine wires of any metal placed between them, all of which, by the use 15 of adhesive materials and by pressure, are wrought into form and substance as one sheet or fabric.

The drawings show one of the many forms of my improved fabric, Figure 1 being a sectional end view, and Fig. 2 a view showing the fabric with the outer layer or layers partly removed, so as to show one form of and way in which the interior fibrous material is used.

In the drawings, A represents one of the 20 outer sheets or layers, B another, and C C the intervening fibrous material.

To produce this improved fabric I take sheets, strips, or layers of paper or other material, any or all of which may be plain, printed, embossed, plaited, fluted, corrugated, perforated, woven, or otherwise prepared or ornamented, and place between them fibers of the same or of other materials, in the form of threads, cords, twines, braids, tapes, ribbons, or 25 straw, or fine wire of any metal, severally or in combinations of two or more of such fibrous materials, in order to secure strength and variety in design or styles. When such sheets, strips, or layers are so imposed or superimposed one 30 upon another, and the fibrous material or wire is placed between them, the whole is made by the use of suitable adhesive material and by pressure upon it, to adhere and become as one sheet. The sheets, strips, or layers, whether 35 plain or otherwise, may be imposed, superimposed, or laid one upon another to any extent as to number, and in any desired order, and

one or more of the articles used to give it tensile strength—such as threads, cords, twines, braids, tapes, ribbons, straw, or wire, or 40 equivalent articles—may be used in such quantities, combinations, and positions as may be required in the production of the various qualities and styles of fabric desired. The fibrous substances—such as thread, tape, wire, &c.— 45 may be placed parallel with each other, or they may be placed in any other position desired, either thickly covering the inner surfaces of the sheets, layers, &c., or being sparsely scattered over the same. The edges of one or 50 more of the sheets, strips, &c., may be folded back or turned over or in, so as to form a hem or binding having one or more of the wires or threads, &c., inclosed therein. By the use of different colors in the sheets, strips, or layers, 55 and of printed, painted, perforated, cut, or woven designs, the threads, wires, cords, tapes, ribbons, &c., having been properly placed, suitable adhesive material having been applied, and the whole subjected to the requisite pressure, a fabric is produced having one 60 or more colors or designs upon one face or side and another color, colors, or designs upon the other side, and which presents, when between the eye and the light, other colors or 65 tints, figures, letters, or designs not seen upon either face.

The embossed, plaited, or otherwise ornamented side of the sheets, strips, &c., imposed or interposed may be upon the outside of or 70 within the fabric, their relative positions being determined by the requirements of style, quality, &c. When a plaited sheet or layer is interposed between two or more plain smooth ones, the fabric presents a smooth or plain and even 75 appearance, except between the eye and the light, when the outline appears, as is also the case when figures, letters, or designs are employed in like manner. This improved fabric may be made in a variety of styles, either 80 ornamented or plain, care being taken to give it the necessary tensile strength by having fibrous substances interposed between the sheets, layers, strips, &c., and it may be adapted to use for a variety of purposes, some 85 of which have already been mentioned.

I am aware that a fabric has heretofore been patented or described having longitudinal threads incorporated between two sheets of

paper-pulp in the process of manufacture. I do not, however, claim such as my invention; but

What I do claim, and desire to secure by 5 Letters Patent, is—

1. A fabric composed of layers of paper, or other suitable materials, having between them the fibers of the same or of other materials in the form of threads, cords, tapes, ribbons, or 10 fine wires of any metal, all of which, by pressure and the use of adhesive materials, are wrought into form and substance as one sheet or fabric, substantially as set forth.

2. A fabric composed of layers of paper or other suitable materials, having between them 15 fibers of the same or of other materials running in the direction of the length of the fabric, and substantially parallel with each other, as shown and described.

ALBERT L. JONES.
